UNITED STATES PATENT OFFICE

123,931

DESIGN FOR A TRANSFORMER

Elmer J. Zelt, Fort Wayne, Ind., assignor to General Electric Company, a corporation of New York

Application February 16, 1940, Serial No. 90,304

Term of patent 14 years

To all whom it may concern:

Be it known that I, Elmer J. Zelt, a citizen of the United States, residing at Fort Wayne, in the county of Allen, State of Indiana, have invented a new, original, and ornamental Design for a Transformer, of which the following is a specification, reference being had to the accompanying drawing, forming a part thereof.

In the drawing, Fig. 1 is a perspective view of

a transformer showing my new design, Fig. 2 is a side elevation, and Fig. 3 is an end elevation thereof. The other side of the transformer is the same as that shown in Figs. 1 and 2.

I claim:

The ornamental design for a transformer, substantially as shown and described.

ELMER J. ZELT.
